SURGICAL AND DENTAL CHAIR.

No. 562,391.

Patented June 23, 1896.

UNITED STATES PATENT OFFICE.

AARON P. GOULD, OF CANTON, OHIO.

SURGICAL AND DENTAL CHAIR.

SPECIFICATION forming part of Letters Patent No. 562,891, dated June 23, 1896.

Application filed February 25, 1895. Serial No. 539,561. (No model.)

To all whom it may concern:

Be it known that I, AARON P. GOULD, a citizen of the United States, and a resident of Canton, county of Stark, State of Ohio, have 5 invented a new and useful Improvement in Surgical and Dental Chairs, of which the following is a full, clear, and exact description, reference being had to the accompanying drawings, making part of this specification.

10 My invention relates to certain improvements in surgical and dental chairs; and it consists in providing means for raising and lowering the chair-body, and for supporting it in desired elevation.

15 With these ends in view my invention consists of certain features of construction and combination of parts, as will hereinafter be described and claimed.

Figure 1 of the accompanying drawings is 20 a view in perspective illustrating my invention. Fig. 2 is a vertical section. Fig. 3 is horizontal section on line $y-y$ of Fig. 2. Fig. 3^a is a detail perspective of a portion of the base and the link o . Fig. 4 is a vertical section on lines $z-z'$, Fig. 3. Fig. 5 is a similar view on line $Y-Y$, Fig. 4. Fig. 6 is a view of the inner end of the lifting-lever from the inside, showing the pawl and trip. Fig. 7 is a side view of the rack-wheel. Fig. 8 is a side 25 view of the inner end of the lifting-lever from outside, showing the lever-lifting spring. Fig. 9 is an elevation of the lowering mechanism from the front side. Fig. 10 is a longitudinal section of the air-cylinder. Fig. 11 is a longitudinal section through the head-rest and its support. Fig. 12 is a section through the rack-wheel and a fragment of the base, showing the lifting-pawl in engagement with the rack-teeth. Fig. 13 is a similar view showing 30 the pawl out of engagement with the rack-teeth.

A denotes the base, having upwardly-projected portions B, to which is pivotally secured an arm, as C, to the forward end of 45 which is pivotally secured a rearwardly-projecting arm D. At the upper end portion of the arm D is provided a circular seat or body-support a , pivotally secured to the arm by the pivots b , and adapted to be tipped or 50 rocked about its pivotal connection with the arm; and to secure the support a and the chair-body E, supported thereon, in desired

adjustment about its pivotal connection with the arm D a rack c is provided, as shown in Fig. 2, secured to the arm D, and a spring-pawl d^* is pivoted to the support, as shown at e , said pawl having pedals f projected therefrom, by which the operator may disengage the pawl from the rack, the spring g serving to hold the pawl in engagement with the rack, thereby securing the parts in adjusted position.

To raise the chair-body E, a spur or rack wheel G is loosely mounted on a non-rotative shaft h , secured in the base A, said wheel 65 having engagement with the rack H, the upper end of which has a pivotal engagement with the arm C, the lower end to pass down into the base, as shown in Fig. 2.

The rack-wheel G has in its side a recess j , in which is loosely mounted on the sleeve k , or if, preferred, on the shaft h , a clutch-head I, supporting a pawl l , (see Figs. 6, 12, and 13,) the outer end of which will engage the rack-teeth m , provided on the inner surface of the wall of the recess j . To the hub n of the clutch-head I is secured an actuating-lever J. When the outer end of the lever J is raised, the outer end of the pawl will be carried down to be in readiness to engage a tooth m , near the bottom portion of the series. The reverse movement of the lever will bring the pawl into engagement with one of the teeth and thereby rotate the wheel G , to raise the rack H, and the arm C, and the parts connected thereto; and to impart a simultaneous upward movement to the arm D, and the chair-body supported thereon, a chain of gear-wheels 1 2 3 4 5 are loosely mounted on pins or studs secured in the 75 downwardly-projected side flanges of the arm C. Wheel 1 is connected to the top portion of the base by a link o , pivotally secured to the lugs p , as shown in Figs. 3 and 3^a, and wheel 5 is connected with the arm D 80 by the link q , as shown in Fig. 2.

When the arm C is folded down over the base, the lowest point of adjustment, the upper end of the link o will occupy the position indicated by the dotted lines; the arms having been lowered, will carry the center of the wheel 1 down below the end of the link. Having assumed that position now, as the lever J is pressed down, the pawl l will en-

gage the rack-teeth m , by which the wheel G will be rotated, to raise the rack H and the arm C , which movement will cause the wheels 1 2 3 4 5 to rotate (the wheel 1 being held rotatively to the base by the link o) in the direction indicated by the arrows; wheel 5, having a link connection with the arm D , will raise the arm D up to the position shown in Figs. 1 and 2, or to any desired point of limit of movement. When the lever J is released, the spring z^2 (shown in Fig. 8) will raise the outer end of the lever, by which movement the finger z^3 will engage the top of the base to draw the pawl out of engagement with the rack-teeth m .

To lower the arms C D and chair-body E , a non-rotative shaft r is secured in the base, as shown in Fig. 3, on which is loosely mounted a worm-wheel K , having in its side a recess s , provided with rack-teeth t , as shown in Fig. 5. On the same shaft r is loosely mounted a pinion L , as shown in Fig. 3, having teeth to engage the teeth of wheel G . At the side of the pinion is provided a hub extension u , to which is pivotally secured a series of gravity-pawls w , one or more of which may at all times be in engagement with the rack-teeth t . A worm-shaft, as M , is journaled in the base A , as shown in Fig. 5, to engage the worm-wheel K . At the inner end of the shaft is provided balls a' to prevent friction caused by the thrust of the shaft, and at the outer end of the shaft is mounted a fly-wheel N , having on its inner side or face a ratchet a^2 .

As a break or resistance to a too rapid descent of the chair-body, an oscillating cylinder, as O , is provided, having trunnions at the sides thereof, by which it is supported in the lugs a^3 provided therefor. In the cylinder O is provided a piston-head a^4 , having a small aperture a^5 provided therein, as shown in Fig. 10. On the outer face of the fly-wheel N is provided a cross-bar a^6 , having a series of apertures a^7 provided therein, adapted to receive a wrist-pin a^8 , to which the piston-rod a^9 is connected.

To start the wheel N to rotate and to stop rotation, a pedal-lever P is loosely mounted on the worm-shaft M , between the ratchet a^2 and the base A . To the lever P is pivotally secured the upper end portion of a standard b' , the lower end of which is supported in an aperture b^2 , in the base. About the lower end of the standard b' is provided a coil-spring b^3 , the lower end resting on the base, and the upper end to rest under an outwardly-projected arm b^4 , on which is provided a shoe b^5 , to engage the wheel N . At the upper end portion of the standard b' is pivotally secured a gravity-pawl b^6 , having a nose b^7 , adapted to fall into engagement with the teeth of ratchet a^2 .

To operate the lowering devices, the lever P is pressed down quickly; the nose b^7 of the pawl b^6 , engaging the rack a^2 , will give the fly-wheel N a start, which will be con-

tinued by the pressure of rack H on wheel G , and by wheel G on pinion L , and, through the clutch mechanism, the worm-wheel will be rotated against the worm on shaft M , which will be rapidly rotated to lower the rack H , and the parts supported thereon, the movement of the wheels 1 2 3 4 5 to be reverse to that indicated by the arrows, hereinbefore mentioned.

When the lever or pedal P is pressed down, as before stated, the pawl b^6 will be carried below and out of the reach of the teeth of the ratchet a^2 . To arrest the descent of chair-body, the pedal P will be released, the energy of spring b^3 will raise the pedal and standard until the brake b^5 engages and stops the rotation of the fly-wheel.

As a resistance to a too rapid descent of the chair-body, the hereinbefore-described cylinder and piston connection with the fly-wheel N are provided. In operation, as the wheel N is rotated, the piston-head a^4 is rapidly moved back and forth in the cylinder, which movement is resisted by the air in the cylinder, which, to allow the movement of the piston, as before stated, must pass through the aperture a^5 provided in the head, as shown in Fig. 10, which may be made or sized to determine the speed of the descent of the chair-body.

Q denotes a head-rest support, adapted to slide vertically in a back-support R , that may be secured in vertical adjustment by the set-screw h' . At the upper end of the support Q is provided a forwardly-projected arm h^2 , having hinged to its forward end an overlapping rearwardly-projected arm h^3 , having vertically therethrough an elongated aperture or slot h^4 . To secure the arm h^3 in desired adjustment about its hinged connection with the arm h^2 , a longitudinal aperture h^5 is provided in the arm h^2 , in which is placed a plug h^6 and a set-screw h^7 . By the latter the plug h^6 may be driven against the hinge portion of the arm h^3 , whereby it is held in desired adjustment about the hinge-pin h^8 . On the upper face of the arm h^3 is placed a sliding block h^9 , having at its front end a spherical socket k^1 , and at its middle portion a rubber spring k^2 , and at its rear end an aperture k^{13} , to receive to receive the tightening-bolt k^4 . Over the block h^9 is placed a cap-piece k^5 , adapted to cover the block h^9 , the lower edges not, however, to rest on the face of the arm h^3 . At the under side of the front portion of the cap is provided a spherical socket k^6 , and at rear end portion an aperture k^8 , to receive the bolt k^4 . The cushion-support k^{16} is provided with a ball k^7 , adapted to the spherical socket formed in the block h^9 and cap k^5 . A handle-nut k^9 is turned on the bolt k^4 , to clamp the cap on the ball and the cap and block on the arm h^3 .

In operation the cushion may be moved forward by slackening the handle-nut k^9 and moving the bolt k^4 forward in the slot h^4 , or the parts may be turned out laterally to the arm

*h*³, or rotated about the bolt *k*⁴; and when desired the screw *h*⁵ may be slackened and the arm *h*³ and cushion turned down in front of the back cushion *R* and extended down in front to reach the head of a child. When the handle-nut *k*⁹ is slackened, the rubber-spring *k*² will raise the cap *k*⁵ and release the ball *k*⁷, so that it may be moved or rotated in the spherical socket and secured in desired adjustment by the handle-nut *k*⁹.

Having thus fully described the nature and object of my invention, what I claim is—

1. The combination with the base and seat of a chair, an arm *C* pivoted to the base, and an arm *D* pivoted to the seat, said arms being pivoted together of a lifting mechanism, comprising a rack and rack-wheel, the latter having peripheral teeth, and internal teeth formed in its side, a foot-lever provided with a pawl to engage the internal teeth, a train of gear-wheels supported on the arm, *C*, one of said wheels having a link connection with the base, and another a link connection with the arm, *D*, whereby the movement of the arm, *C*, may be transmitted to the arm, *D*, substantially as set forth.

2. The combination in a surgical and dental chair, with the base and seat of the same of a lowering mechanism, comprising a rack, a rack-wheel, a worm-wheel and worm, the pinion, *L*, and clutch devices between said pinion and the worm-wheel a wheel rotated by said worm, and an oscillating cylinder, a piston-head in said cylinder, a piston-rod connected with said wheel, whereby the piston-head is moved in the cylinder against the air therein, to resist the movement of the wheel and worm to regulate the descent of the chair-body, substantially as set forth.

3. The combination in a surgical and dental chair, with the base and seat of the same of a mechanism to start and stop the movement of the lowering mechanism, comprising a fly-wheel that is rotated by the descent of the chair-body, a rack-wheel secured to said fly-wheel, a pawl to engage the teeth of the rack-wheel, a foot-lever to operate said pawl, and a brake to engage the fly-wheel, substantially as set forth.

4. The combination with a head-rest support *R*, of the vertically-adjustable stem, a means for securing said stem in desired vertical adjustment, said stem having a forwardly-projected arm, to which is pivotally secured a rearwardly-projected plate or arm, having a longitudinal aperture therein, and adapted to be rotated about its pivotal connection with the before-mentioned arm, a handle-screw, whereby said arm or plate is secured in desired adjustment about its pivotal connection with the first-mentioned arm, a block to slide on the hinged arm or plate, having at its front end a circular recess, a cap to pass over said block, having a circular aperture to register with the circular aperture in the block, a cushion-frame having a spherical or ball portion adapted to the spherical socket, formed in the block, and the cap, and means whereby the block and cap may be drawn down upon the plate, and the ball, to secure the parts in desired adjustment as set forth.

In testimony whereof I have hereunto set my hand this 15th day of February, A. D. 1895.

AARON P. GOULD.
